UNITED STATES PATENT OFFICE

JAMES E. SCHROEDER, OF HOUSTON, TEXAS

SULPHUR MINING

Application filed March 9, 1922. Serial No. 542,223.

This invention relates to the mining of sulphur from underground deposits and it has special reference to processes and apparatus of the well-known Frasch type.

5 In accordance with the Frasch process, water superheated under pressure is forced down from the surface into contact with the sulphur deposits where it serves to fuse or melt the sulphur, which is thereafter suitably elevated to the surface in the liquid state. To a large extent, the operating economy of such a process depends upon the efficiency or effectiveness of operation of the heating medium in its fusion action upon the sulphur, 15 and this, in turn, is dependent upon the geological formation and structure of the sulphur deposits, and the immediately adjacent strata. If the deposits and neighboring strata are porous in character and contain fissures, crevices and other voids, the heating medium necessarily runs off or escapes and much of the heating medium is lost and the heat thereof uselessly dissipated in regions remote from the sulphur deposits. A similar condition arises in a sulphur mine under 20 operation when a portion of the sulphur has been removed, leaving large voids which must be uselessly filled with the heating medium as the work progresses, and in which the heat is 25 dissipated.

Appreciating these difficulties and the resulting inefficiency and ineffectiveness flowing therefrom, it is one of the objects of the present invention to improve the efficiency of sulphur mining of this general character by promoting the effectiveness of the heating medium upon the sulphur deposit in such manner as to locally confine the heating medium to a large extent to the immediate area of the 30 deposits, thereby conserving its heat and applying it directly to the sulphur so that it will be expended effectively and expeditiously in performing its intended function.

To this end, it is proposed to introduce 35 compressed air or other suitable medium, having relatively poor heat conducting properties, into the region immediately above the sulphur deposit so as to fill the voids and thus prevent the escape of the heating medium 40 and the wasteful dissipation of its heat. A

layer or blanket of a relatively good heat-insulating medium under pressure is thus provided above and in proximity to the sulphur deposits. As the mine is worked and sulphur gradually removed, this blanket of 55 compressed air or the like is progressively lowered by the supply of increased volumes thereof so as to fill the voids left by the removal of sulphur. The air or other heat insulating medium is introduced by means of a 60 suitable well or casing through which it is forced, and suitable apparatus is provided to enable the operator to determine the exact depth of the air layer or blanket, with respect to the location of the sulphur deposit being 65 mined. In this way, the operation may be intelligently conducted and effective and efficient operation of the heating medium may be insured. Obviously, the heat-insulating medium may be utilized in certain formations 70 merely for the purpose of filling the voids left by the removal of the sulphur.

In some cases, it will be found expedient to provide an auxiliary casing or well extending to a region somewhat below the area of the deposit operated upon and to remove therefrom a portion of the water or heating medium that has largely given up its heat and thus cooled off to a considerable degree, a circulation of the heating-medium being thus 75 provided. Preferably, water that has dropped in temperature to approximately 200° F. is thus removed, and so long as it is above that temperature it is allowed to remain in the mine. Although below the melting point of sulphur, water of a temperature of 200° F. has a very beneficial effect upon the deposit and contributes to the effectiveness of the heating medium being constantly introduced. 80

A further object of the invention is to provide a process of sulphur mining that shall be especially adapted for operation upon deposits occurring in a mound-like geological formation, where the bulk of the deposit lies in the form of an annulus and which contemplates operating upon the deposit by means of producing wells initially located at distributed points around the inner periphery 85 of the deposit and subsequently through the 90 95 100

agency of wells progressively located at more remote points and at increasing depths whereby substantially the entire sulphur content of the deposit is eventually removed.

5 These and other objects of the invention and features by means of which they are accomplished will be understood by those skilled in the art from the following description of the invention as illustrated in the accompanying drawings, in which

10 Fig. 1 is a more or less diagrammatic sectional view of a typical mound-like geological formation containing a deposit of sulphur, together with certain apparatus constructed 15 and arranged in accordance with the present invention and by which the present process may be practiced,

15 Fig. 2 is a diagrammatic plan view of the typical geological formation of Fig. 1 and 20 showing the arrangement and distribution of the sulphur deposit, together with the location of the apparatus necessary for conducting the present process, and

25 Fig. 3 is a view similar to Fig. 1, showing the apparatus of the present invention as applied to a somewhat different geological formation.

30 Referring particularly to Figs. 1 and 2, as illustrative of the apparatus as applied to a typical mound-like formation or occurrence of the sulphur deposit, the formation illustrated embodies a plurality of strata representing a so-called "surface" formation 10, lime-rock 11, sulphur deposit 12, anhydrite 35 13 and salt core 14. In the particular example shown, the mound-like geological formation is such that the main bulk of the sulphur deposit occurs on the slope of the anhydrite in the general form of an annulus, 40 as indicated in heavy section lines in Figs. 1 and 2, although a relatively thin layer of sulphur deposit lies immediately above the substantially flattened top thereof, as illustrated in light section lines of said figures. As will 45 be apparent from the drawings a relatively thick stratum of cap or lime rock overlies the thin layer of deposit and covers a very considerable area. This cap or lime rock contains much water and embodies many large 50 voids.

55 The mining of the sulphur deposit is effected in a somewhat similar manner to that of the well-known Frasch process, and for this reason the apparatus and mode of operation will only be briefly set forth. The removal of the sulphur from the underground deposit is advantageously accomplished by means of a plurality of so-called "producing" wells P, which are so distributed with 60 respect to the mound-like geological formation as to be located at different points throughout the annulus embodying the bulk of the sulphur deposit. These producing wells are of like construction and similar 65 to those employed in the Frasch process and

each may conveniently comprise an outer casing 20 which extends from the surface S to approximately the upper contour of the sulphur deposit 12, and a so-called "top water" casing 21 disposed within the outer casing 20 and intimately connected or sealed thereto at a point 22 somewhat above the upper contour of the sulphur deposit. This top water casing is perforated throughout the length of the sulphur deposit and terminates at substantially the upper anhydrite contour in an extended projection or anchor 23. Within the casings, hereinbefore mentioned, is a so-called "bottom water" casing 24 extending from the surface to a point illustrated by joint 25 below which the casing is extended by means of a short perforated strainer 26 to a suitable gasket or collar 27, the collar being preferably located a few feet above the upper contour of the anhydrite 13 and within the sulphur deposit. An extension of this bottom water casing 25 is provided in the form of a so-called "sulphur" strainer 28 projecting somewhat below the collar 27 and disposed within the lower perforated end of the top water casing 21. The lower end of this strainer 28 is closed by means of a disc 29. A pipe 30 for the removal of the liquid sulphur is arranged within the other casings and extends through the collar 27 and into the sulphur strainer 28 for a short distance. In addition, an air pipe 32 is centrally located within the several casings above mentioned and extends from the surface to a point within the sulphur deposit somewhat above the location of the strainers 26 and 28 already mentioned.

It will be understood that the relative dimensions and proportions illustrated are by no means accurate, but are merely for the purpose of indicating in a general way the arrangement and construction of the producing well.

In operation, superheated water and steam are delivered from a boiler or boilers 35 through a pipe 36 to the upper end of the casing 20 and this water and steam is forced down through the casing and, at the point 22, into the "top water" casing 21 from which it emerges through the perforations provided therein. Additional superheated water and steam at a higher pressure is forced into the "bottom water" casing 24 from the boiler or boilers 35 through a pipe 36' and a suitable force pump 37. This water and steam is forced down the well and emerges through the perforations in the lower end of the "bottom water" casing; comprising the strainer 26. In this way it is insured that the heating medium is delivered into the surrounding sulphur deposit at a point adjacent the lower end of the well.

This highly heated water and steam, thus delivered to the sulphur deposit adjacent the lower end of the well, permeates the adjoin- 130

ing sulphur-bearing material and the heat thereof eventually fuses, melts or liquefies the sulphur content of the deposit. The molten sulphur collects around the bottom 5 of the well and is removed in any suitable manner. As illustrated in the drawings, a convenient mode of removing or elevating the liquid sulphur to the surface is by means of air pressure through the agency of an air 10 compressor 40 which compresses air to a high degree and delivers it through a pipe 41 to the upper end of the air pipe 32, whereby it is conducted downwardly into the well. The molten sulphur, collecting around the 15 bottom of the well, flows inwardly through the perforated lower end of the top water casing 21 and thence through the sulphur strainer 28 after which it rises through the pipe 30 and is elevated to the surface in a well-known manner by the highly compressed air emerging from the pipe 32 near the bottom of the well. The sulphur as it reaches the surface is discharged from the upper end of the pipe 30 through a pipe 43 20 and is delivered into a suitable vat or other receptacle 44.

The structure and operation of the producing well per se, just described, is in accordance with the well-known Frasch process and 30 in itself forms no part of the present invention, except as it enters into combination with certain other features thereof to be hereinafter set forth.

The essence of the Frasch process, just described, lies in the fusion or liquefaction of the sulphur content of the deposit by means of the introduction of a heating medium. It is manifest that the efficiency and commercial feasibility of mining sulphur in this manner 40 depends upon the effectiveness and efficiency of the heating medium toward its intended purpose. Obviously the heat efficiency is to a large degree dependent upon the geological structure of the adjoining strata. If the overlying stratum or formation be such as 45 to embody voids, fissures, or crevices to a considerable degree, much of the heat of the heating medium is permitted to escape and is uselessly dissipated.

The present invention is directed to the 50 conservation of the heating medium to locally confine its operation to the sulphur deposit where substantially all of the heat is usefully employed in a localized area whereby economy and efficiency of operation are secured.

This is accomplished by preventing the useless dissipation of heat in filling the voids of the over-lying cap or lime rock 11 with a 60 heat-insulating medium, such as compressed air. To this end, an air well A is located at the highest point of the lime-rock stratum containing open voids, which, in the present instance, is assumed to be substantially the mid-point of the area denoted in

Fig. 2 by the dotted line 5, which indicates the boundary of the relatively thin sulphur deposit lying over the flattened top of the anhydride stratum.

The air well A comprises an outer casing 50 which is sunk to substantially the upper contour of the cap or lime-rock 11. This casing may, if desired, be extended into or through the cap rock, in which event, it is preferably perforated. A pipe 51 is disposed 70 therein and normally projects through the cap rock to the upper surface of the relatively thin layer of sulphur deposit 12. The upper end of the pipe 51 is provided with a controllable valve 52, while the upper end of the casing 50 communicates by means of a pipe 53 with an air compressor 54 of suitable construction. The pipe 51 is termed a "theft" pipe and is adapted to be adjusted 75 in position, as desired, in order to definitely determine the depth of the air layer with respect to the location of the sulphur bed being operated upon. Normally the lower end of the theft pipe 51 lies in the 80 plane of the upper contour of the sulphur 85 deposit 11.

In order to fill the voids of the cap or lime-rock 11, lying immediately above the stratum of sulphur-bearing material, air at a high degree of compression is forced down through 90 the casing 50 and into the voids of the cap rock, thereby completely filling the voids and thus preventing the entrance therein of the heating medium. In this way the useless dissipation of the heating medium, which is necessarily incident to processes of this character 100 that have been employed in the past, is substantially obviated. The compressed air, thus introduced, forms an extended horizontal layer or blanket immediately above the sulphur-bearing deposit, as is shown in horizontal section lines in Figs. 1 and 2. Inasmuch as air is a very good heat-insulating medium, this air layer serves effectively to locally confine the heat of the heating medium to the 105 region of operation upon the sulphur deposit.

The degree of compression of the air, thus introduced to form the heat insulating layer, depends upon the particular conditions and geological formation, and is determined 110 largely by the depth at which the sulphur deposit occurs. More strictly speaking, it is dependent upon the hydrostatic head existing by reason of the depth of the deposit below sea level. Without attempting to define the 115 degree of compression necessary, it should be understood that air should be compressed sufficiently to overcome the existing hydrostatic head at the particular depth of the deposit. The thickness of the layer of air or other heat-insulating medium is determined 120 by the location of the lower end of the "theft" pipe 51 and should be such that all the voids of the cap rock are filled. If water emerges 125 from the upper end of the theft pipe 51, it is 130

an indication that additional amounts of air must be introduced in order to lower the air layer to a point corresponding to the lower end of the theft pipe. The depth of the air layer may be ascertained by adjusting the height of the theft pipe until air begins to emerge therefrom. By means of the theft pipe, therefore, it is possible to definitely determine the depth of the air layer whereby the operation may be intelligently carried on so as to insure the filling of all of the voids. By reason of the high temperature existing in the water in the neighborhood of the air layer, this blanket of air can be maintained at relatively small cost inasmuch as the air is practically insoluble under these conditions of heat.

The utilization of the heat-insulating layer of air, as just described, is especially advantageous when operating upon sulphur beds occurring in a stratum of the general formation indicated in Figs. 1 and 2, where the bulk of the sulphur deposit lies in the form of an annulus and a very large area of cap rock filled with voids occurs above and within the annulus. With such a geological formation, it is evident that the aggregate of the voids of the overlying cap rock is enormous and, therefore, an immense amount of heat would be uselessly dissipated therein, were no suitable provision made for confining it to the operating area.

As the operation is carried on and the sulphur content of the deposit gradually melted and removed, the area of voids is greatly increased. Therefore, as the sulphur is removed and the production gradually lowered, the layer of heat-insulating medium is also progressively lowered to fill the voids left by the removal of the sulphur. In a formation, such as illustrated in the drawings, the air layer may be advantageously lowered at least until it reaches the upper contour of the anhydrite, thereby closing off all of the area above it from the dissipation of heat and confining the heat medium to localities where it will be effective upon sulphur deposits.

Obviously, the utilization of the air layer is not restricted to geological formations embodying cap rock filled with voids, but may be advantageously employed under other conditions for the purpose of merely filling the voids left by the removal of the sulphur content.

In carrying on the present process upon a mound-like formation such as illustrated, it is particularly desirable and expedient to begin the removal of sulphur by means of wells located around the inner periphery of the annular deposit, where they are so disposed as to initially remove the sulphur occurring at the highest points of the deposit. In this way, any molten sulphur that is liquefied and not removed flows to lower

levels and will subsequently be reached and elevated to the surface as production is later carried on by other wells sunk to greater depths.

As the production from the first producing wells P is reduced to such an extent as to indicate that the sulphur content above and adjacent thereto has been substantially removed, these wells are closed off and new wells P' are drilled and operated. These new wells are located somewhat further away from the air well A and extend down into the sulphur deposit to lower depths. The producing wells are thus progressively moved outwardly from the center of production and at the same time sunk to greater depths.

This mode of conducting the production is of especial importance in that it insures that substantially the entire sulphur content is eventually removed.

The present process also contemplates the provision of a plurality of so-called "bleed" wells B which are located beyond the producing wells and at even greater depths. These bleed wells are for the purpose of insuring a circulation of the heating medium and removing a portion of the water introduced through the producing wells which, upon giving up its heat in its fusion action upon the sulphur, finds its way down to lower levels. These wells comprise a casing 60 extending from the surface to the desired depth below the lower ends of the producing wells. The upper end of the casing is provided with the regulatable valve 61 and discharge pipe 62 to carry off the water emerging therefrom. A suitable thermometer or other temperature-indicating device 63 is provided at the upper end of the casing 60 to determine the temperature of the outflowing water. In conducting the process, the valve is kept open to permit the discharge of cool water until the thermometer 63 indicates a temperature in the neighborhood of 200° F., at which time the valve 61 is closed. In this way a portion of the water which is partially cooled, is periodically or, if desired, continuously removed to permit the supply of additional amounts of heating medium, thereby creating a more or less definite circulation instead of allowing the heating medium to become stagnant. The water in the sulphur-bearing material is thus maintained above a temperature of 200° F., and although this temperature is below the melting point of sulphur, it has a beneficial effect upon the sulphur content and increases the efficiency of the heating medium.

Referring to Fig. 3, the geological formation therein shown differs slightly from that of Figs. 1 and 2, in that the contour of the various strata is more nearly horizontal,—that is, the strata lie in more or less horizontal layers. The apparatus and mode of op-

eration employed in connection with such formations is similar to that already described and differs only in that, by reason of the horizontal disposition of the formation, the producing wells extend down through the layer of compressed air or other heat-insulating medium. The process, so far as its operation is concerned, is similar to that already described although it is necessary to make suitable provision for preventing the escape of the air cushion while drilling through the stratum in which the air layer exists. During this drilling operation, it is desirable to thoroughly seal the opening between the well casing and the drill stem by continually introducing therein from the surface a medium ladened with mud or other suitable material. Any convenient means of introducing this mud-laden fluid may be employed. Of course, as soon as the well is drilled through the stratum in which the air layer exists and the casing subsequently lowered therethrough, there is no further necessity of introducing more mud-laden fluid to seal the well against the escape of the air, inasmuch as the casing itself completely performs this function.

Although the invention has been set forth as embodying more or less specific details of construction, arrangement and location of parts and mode of operation, it will be understood that the invention is not so restricted and that many modifications may be made therein without departing from the spirit and scope of the invention, therefore, only such limitations should be imposed as are indicated in the appended claim.

I claim:

Apparatus for mining sulphur from underground deposits having, in combination, a producing well for introducing a heating medium into the deposit to effect the melting of the sulphur content and for removing the sulphur so melted, an air well extending down to the highest point of the sulphur-deposit for conducting air to form a heat-insulating layer immediately above the deposit, means connected to said air well for highly compressing the air and forcing it down the well and a theft pipe disposed within said air well for determining the depth of the air layer above the deposit.

In witness whereof I have hereunto set my hand and seal this 15th day of February, 1922.

JAMES E. SCHROEDER.
